UNITED STATES PATENT OFFICE.

FRANZ FORTELKA, OF VIENNA, AUSTRIA-HUNGARY, ASSIGNOR OF ONE-HALF TO WILHELM LEITNER, OF SAME PLACE.

MAGAZINE FOR FIREARMS.

SPECIFICATION forming part of Letters Patent No. 669,919, dated March 12, 1901.

Application filed August 16, 1900. Serial No. 27,074. (No model.)

To all whom it may concern:

Be it known that I, FRANZ FORTELKA, a citizen of the Empire of Austria-Hungary, residing at Vienna, in the Province of Lower Austria, in the Empire of Austria-Hungary, have invented certain new and useful Improvements in Magazines for Firearms; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to magazine-firearms, and has for its object the construction of a drum-shaped magazine situated underneath the breech-receiver and containing a smaller central spring-rotated drum around which the cartridges are placed, said inner drum having a feeding-web, by means of which the cartridges are brought in succession to the feeding-chamber of the receiver.

In the annexed drawings a magazine of this kind is shown, of which—

Figure 1 is a longitudinal and Fig. 2 a transverse section.

In both figures similar letters of reference indicate corresponding parts.

The lower part of the breech-receiver is formed into a conical or cylindrical drum or easing *a*, in the mathematical line of axis of which a pin or shaft *b* is situated. Upon this pin *b* is placed the rotary inner drum *d*. Inside this drum *d* and upon the pin *b* is placed a helical spring *c*, the one end of which is fastened to the pin *b* and the other to the drum *d*. The drum *d* is provided with a feeding-web *f*, which is shaped to correspond to the form of the cartridges and which moves in the space between the inner and outer drums.

The drum *a* is open at its top part and communicates with the breech-receiver, in which is guided the breech-bolt *g*. This communicating opening between the magazine and the receiver is closed off on one side by a partition *h*. Opposite this partition *h* a spring *k* is attached to the interior surface of the drum *a*, which is also provided with a recess *i*, into which the spring *k* may enter when it is depressed. This spring *k* serves for holding in

place the cartridge already entered into the receiver and the cartridge next to it in the magazine.

When the magazine is empty, the feeder *f* stands opposite the partition *h* in the position indicated by dotted lines in Fig. 2. The magazine is charged by pushing one cartridge after the other through the breech-receiver into the drum *a*, each cartridge passing underneath the retaining-spring *k*. By the introduction of the cartridges in this manner the drum *d*, with the feeder *f*, is turned in a direction opposite to the direction of the force exerted by the spring *c*, whereby this latter is tightened. When the magazine is filled with cartridges, the feeder *f* stands facing the inner side of the partition *h*, as shown in Fig. 2. After the first cartridge placed into the receiver has been fired and ejected the next cartridge in the magazine passes underneath the spring *k* into the receiver, from whence it is pushed into the firing-chamber by the breech-bolt, while the next cartridge is retained in the magazine by the spring *k*. This operation may be continued until the magazine has been emptied.

Having now described my invention, what I claim as new, and wish to secure by Letters Patent, is—

In magazine-firearms, the combination with a sliding breech-bolt *g*, of a drum-shaped magazine *a*, open at the top, a partition *h* projecting inward from one side of the opening, a spring *k* secured at the opposite side of the opening, the interior surface of the drum being recessed at *i* to receive the spring *k* when compressed, a shaft *b* centrally mounted in the magazine, an interior drum *d* loose on the shaft, a spring *c* coiled about the shaft in drum *d* and secured at its ends to said shaft and drum respectively, and a feeding-web *f* on drum *d* projecting across the space between the drum *d* and the magazine *a*, substantially as described.

In testimony that I claim the foregoing as my invention I have signed my name in presence of two subscribing witnesses.

FRANZ FORTELKA.
